United States Patent Office

Des. 216,003

Patented Nov. 18, 1969

216,003

PORTION CONTAINER FOR FOOD OR BEVERAGE

James D. Smith, South Buffalo Township, Armstrong County, Pa., assignor to Aluminum Company of America, Pittsburgh, Pa., a corporation of Pennsylvania

Filed Nov. 21, 1968, Ser. No. 14,558

Term of patent 14 years

Int. Cl. D9—04

U.S. Cl. D9—220

FIG. 1.

FIG. 2.

FIG. 3.

FIG. 1 is a top plan view of a portion container for food or beverage.

FIG. 2 is a side elevational view thereof.

FIG. 3 is a cross-sectional view thereof taken along line III-III of FIG. 1.

I claim:

The ornamental design for a portion container for food or beverage, substantially as shown.
